W. E. ENDREZZE
CIRCULAR PACKING CUTTER

Filed April 28, 1927

Patented Feb. 28, 1928.

1,661,136

UNITED STATES PATENT OFFICE.

WILLIAM EUGENE ENDREZZE, OF BUTTE, MONTANA.

CIRCULAR-PACKING CUTTER.

Application filed April 28, 1927. Serial No. 187,280.

The present invention relates to improvements in cutting devices, and has reference more particularly to a simple and efficient means for cutting out washers of different sizes from a blank of rubber, fiber, leather, or the like.

One of the important objects of the present invention is to provide a cutting device of the above mentioned character wherein the same includes a tubular stock, the same being formed with a pair of independent transversely extending slots in which are slidable the inner end portions of a pair of superposed cutter carrying arms, means being provided for independently securing each of the arms in its slot in any radially adjusted position.

A further object of the invention is to provide a cutter of the above mentioned character which will save considerable time and labor in cutting out washers from a blank, the device at all times being positive and efficient in its operation.

A still further object is to provide a cutting device of the above mentioned character which is simple in construction, inexpensive, strong and durable and further well adapted to the purpose for which it is designed.

Other objects and advantages of the invention will become apparent from the following description taken in connection with the accompanying drawing.

In the accompanying drawing forming part of this application:—

Figure 1 is a side elevation of the circular packing cutter embodying my invention.

Figure 2 is a bottom plan view thereof.

Figure 3 is an end elevation.

Figure 4 is a side elevation of the tubular stock.

Figure 5 is a side elevation of the screw threaded plug and the centering point carried thereby, and

Figure 6 is a side elevation of a bit brace engaging member which may be employed in place of the threaded shank carrying a handle on its upper end.

In the drawing wherein for the purpose of illustration is shown the preferred embodiment of my invention, the numeral 1 designates a tubular vertically disposed stock the upper and lower ends are internally threaded. In the present instance the outer cross sectional shape of the stock is hexagonal, although it is to be understood that I

do not wish to limit myself to such shape. The stock 1 is formed with a pair of independent transversely extending slots designated by the numerals 2 and 3, respectively. The lower slot is substantially rectangular in cross section, while the upper slot 3 is dove tailed in cross section, and this is clearly shown in Figure 4 of the drawing. The purpose of forming the slots in this particular manner will be hereinafter more fully described.

Also forming an important part of the present invention are the cutter carrying arms 4 and 5 respectively, the same being of a suitable length and formed at their outer ends with depending cutters 6 and 7, respectively. These arms 4 and 5, are disposed in superposed relation and the lower arm 4 is substantially rectangular in cross section and is adapted for radial slidable movement through the rectangular shaped slot 2 formed in the lower end portion of the stock 1. The upper arm 5 is substantially dovetailed in cross section and is adapted for slidable movement through the dove tailed slot 3 also formed in the stock 1, and due to the arrangement of these stocks, the lower face of the uppermost arm 5 will be disposed in engagement with the upper face of the lower arm 4 and this construction is clearly shown in Figure 1 of the drawing.

The arms 4 and 5 are provided with graduations on the side edges thereof as also clearly shown in Figure 1 whereby the arms may be properly adjusted in order to ascertain the proper size of the washer which is to be cut from a blank when the device is in use.

An externally threaded plug such as is shown at 9 with reference more particularly to Figure 5 in the drawing is formed with a hexagonal head 9 to facilitate the turning thereof, and this plug is adapted to be threaded into the lower threaded end of the stock 1, and the upper end of the plug is reduced as at 10 for engagement with the bottom face of the portion of the lower arm 4 which is disposed within the slot 2 so that the upper face of this arm will be locked in binding engagement with the shoulders 11 formed in the top of the slot 2 whereby the arm 4 will be locked in its properly radially adjusted position against sliding movement with respect to the stock 1.

Extending downwardly from the bottom

of the threaded plug 8 is the centering point 12.

For the purpose of locking the upper arm 5 against sliding movement, I provide the shank 13 which is adapted to extend downwardly in the upper open end of the tubular stock 1. An enlarged threaded portion 14 is formed on the upper portion of this shank for threaded engagement within the upper 10 internally threaded end of the stock 1 and secured on the threaded portion 14 is the handle 15 to facilitate the turning of the shank so that the inner or lower end of the same will be brought into engagement with 15 the upper face of the arm 5 to force the lower face of the arm into binding engagement with the beveled sides of the dove tailed slot 3 formed in the stock 1. Furthermore, this handle 15 provides a means for rotating the 20 stock and the cutter carrying arms when the device is in use.

In using the device, the plug 8 is loosened and the arm 4 is radially adjusted to the required radius. The plug is then tightened 25 for locking the lower arm 4 in its properly adjusted position. The handle 15 is then loosened to disengage the lower end of the shank 13 from the upper arm 5 and the arm 5 is radially adjusted to the outer radius 30 whereby the cutters 6 and 7 will be properly spaced from each other to form a washer of the desired size, and the handle 5 is then rotated in the reverse direction to secure the arm 5 in its proper adjusted position. 35 The centering point 12 is then pressed downwardly into the blank which may be of rubber, fiber, leather or the like and by actuating the handle 15 in one direction a rotary movement will be imparted to the 40 stock 1 and the cutters 6 and 7 will cut an annular packing ring from the blank when a complete circle has been made by the stock 1.

In place of the shank 13 and the handle 45 15 and associated therewith may be em-

ployed the shank 16 which is formed at its upper end with a bit-brace engaging portion 17. Otherwise this shank is the same as the one heretofore described. With a shank of the construction just described, a bit-brace 50 may be used in lieu of the handle for actuating the device to effect the rotation thereof.

A device of the above mentioned character may not only be used for cutting out washers, but can also be used for various other purposes as for example removing the top from a can or cutting circular members from wood stock. The simplicity of my device enables the parts to be readily and easily adjusted and furthermore will at all times 60 be positive and efficient in its operation.

While I have shown the preferred embodiment of my invention it is to be understood that minor changes in the size, shape and arrangement of parts may be resorted 65 to without departing from the spirit of the invention and the scope of the appended claim.

Having thus described the invention, what I claim as new is:—

In a device of the class described, a tubular stock, provided with a pair of independent transverse slots in the lower end portion thereof, a pair of superposed arms slidable through the respective slots, a depending cutter on the outer end of each arm, means for adjustably securing the arms in their respective slots against sliding movement, said means comprising a plug threaded in the lower end of the stock and adapted 70 to engage the portion of the lower arm which is disposed in the lowermost slot, a shank extending downwardly into the upper end of the stock and adapted to engage a portion of the uppermost arm which is disposed within the uppermost slot in the stock, and a centering point extending downwardly 75 from said plug.

In testimony whereof I affix my signature.

WILLIAM EUGENE ENDREZZE.
